UNITED STATES PATENT OFFICE.

ALEXANDER PUJOLS, OF FORT SCREVEN, GEORGIA.

DESIGN FOR A SHAVING-SET HOLDER.

40,622.

Specification for Design.

Patented Apr. 12, 1910.

Application filed February 8, 1910. Serial No. 542,807. Term of patent 7 years.

To all whom it may concern:

Be it known that I, ALEXANDER PUJOLS, a citizen of the United States, residing at Fort Screven, in the county of Chatham and State of Georgia, have invented a new, original, and ornamental Design for a Shaving-Set Holder, of which the following is a specification, reference being had to the accompanying drawing, forming part thereof.

The figure is a front perspective view of a holder showing my new design.

I claim:

The ornamental design for a shaving set holder, as shown.

ALEXANDER PUJOLS.

Witnesses:

M. C. KLEGER,
GEO. CORPELL.
